(57) **CLAIM**

The ornamental design for a portable wireless charging pad, as shown and described.

DESCRIPTION

FIG. 1 is a top plan view of a portable wireless charging pad of my new design;

FIG. 2 is a front perspective view thereof;

FIG. 3 is a front elevation view thereof;

FIG. 4 is front, top, right side perspective view thereof;

FIG. 5 is a top, right side perspective view thereof;

FIG. 6 is a right side elevation view thereof;

FIG. 7 is a rear, top, right side elevation view thereof;

FIG. 8 is a rear, top perspective view thereof;

FIG. 9 is a rear elevation view thereof;

FIG. 10 is a rear, top, left side perspective view thereof;

FIG. 11 is a top, left side perspective view thereof;

FIG. 12 is a left side elevation view thereof;

FIG. 13 is a front, top, left side perspective view thereof;

and,

FIG. 14 is a bottom plan view thereof.

Portions of the article shown in broken lines form no part of the claimed design.
